Thos S. Hudson

UNITED STATES PATENT OFFICE.

THOMAS S. HUDSON, OF EAST CAMBRIDGE, MASSACHUSETTS, ASSIGNOR TO HIMSELF
AND THOMAS LEIGHTON, OF SAME PLACE.

BAROMETER-INKSTAND.

Specification forming part of Letters Patent No. 32,498, dated June 4, 1861; Reissued November
15, 1864, No. 1,820.

To all whom it may concern:

Be it known that I, THOMAS S. HUDSON, of East Cambridge, in the county of Middlesex and State of Massachusetts, have invented 5 an Improved Barometric Inkstand, and do hereby declare the same to be fully described in the following specification and illustrated in the accompanying drawings, of which—

Figure 1, is a top view; Fig. 2, a side elevation; and Fig. 3, a longitudinal section of it.

The inkstand, on which my invention or improvement is made, has an air and ink cistern A, (see the drawings) elevated above 15 the opening or mouth of the neck B, for reception of a pen. In carrying out my improvement, I construct the said mouth of the neck B, with or apply to it a quarter spherical stationary tunnel cap C. The latter and the said mouth may be provided with 20 a quarter spherical cover D, hinged to the upper part of the said cap, as shown at a, and so that the said cover may be turned upward into the position exhibited in Fig. 3.

25 The semi dome or cap, C, projecting as it does beyond the mouth part, B, enables ink to be poured to advantage into the said mouth when the inkstand is in such a posi-

tion that its mouth shall be upward and the plane of its bottom be vertical or about so, 30 in which case, the ink may be poured into the inkstand until such ink may reach the level of the upper edge of the half dome, in which case the fountain A, as well as part of the neck, B, will be full of ink. This having been accomplished the ink will remain 35 in the fountain and be maintained therein and at a level above the mouth of the neck B, by the pressure of the atmosphere when the inkstand is again turned into a position 40 to bring its bottom horizontal. Without the semi-dome C, the inkstand can neither be filled to such extent, nor so advantageously as it can when provided with the dome.

I therefore claim—

The improved barometric inkstand, as made with the semi dome or tunnel, C, or the same and a cover, D, arranged and combined with the ink fountain and its neck and to operate therewith substantially as 50 specified.

THOS. S. HUDSON.
